CAPONIZING INSTRUMENT

Filed Sept. 5, 1929

Inventor
C. F. Cridland

By *Watson E. Coleman* Attorney

UNITED STATES PATENT OFFICE

CLIFFORD F. CRIDLAND, OF CARTER COUNTY, MONTANA

COPONIZING INSTRUMENT

Application filed September 5, 1929. Serial No. 390,607.

This invention relates to improvements in instruments for use in caponizing operations and has for its primary object to provide an instrument so designed that positive engagement of the thread or cord supporting the organ to be removed may be accomplished so that severance of the cord can be effected quickly and easily.

Another object of the invention is to provide an instrument of the above described character so designed that it may be held and manipulated with one hand while the other hand is left free for holding the fowl, thus making it possible for a person to perform the operation without assistance.

The invention will be best understood from a consideration of the following detailed description taken in connection with the accompanying drawing forming a part of the present invention, with the understanding, however, that the invention is not confined to any strict conformity with the showing of the drawing but may be changed or modified so long as such changes or modifications mark no material departure from the salient features of the invention, as expressed in the appended claims.

In the drawing:—

Figure 1 is a plan view of the instrument embodying the present invention.

Figure 2 is a view in side elevation of the forward ends of the jaws.

Figure 3 is a sectional view taken upon the line 3—3 of Figure 1.

Figure 4 is a sectional view taken upon the line 4—4 of Figure 2.

Figure 5 is a sectional view taken upon the line 5—5 of Figure 1.

Referring more particularly to the drawing wherein like numerals of reference indicate corresponding parts throughout the several views, it will be seen that the present improved caponizing instrument is generally in the form of a pair of scissors having the relatively long slender jaws 1, each of which at its rear end is formed to provide a flattened obliquely directed portion 2 which merges into a shank 3 which in turn merges into and terminates in a loop 4 designed to receive a finger of the user. The obliquely

angled portions 2 of the jaws are arranged in crossed relation, as shown, and pivotally secured together by a suitable screw or rivet 5 so that by spreading the loops 4 the forward ends of the jaws will be moved apart, as will be readily understood.

The jaws terminate at their forward ends in the laterally directed fingers 6, which fingers are adapted to be brought into side by side contacting relation when the jaws are closed and one of the jaws has formed integral therewith, upon its underface, a plate 7 which normally overlaps the underface of the adjacent jaw, as shown.

The shanks 3 which together form the handle of the instrument are so formed that when they are brought together they will be in relatively close relation at the points 8 which are adjacent the pivot point 5 and from these points they diverge slightly. One of the shanks carries the sliding latch member 9 which has one end turned to form a hook 10 which is normally engaged over the adjacent shank.

In the use of the present instrument the latch 9 is first moved to the closely spaced parts 8 of the shanks which permits the fingers 6 of the jaws to be opened slightly. After the formation of the necessary incision, the instrument, held in the right hand with the forefinger upon the latch, has the finger carrying ends of the jaws inserted into the incision and is then manipulated to position the cord between the fingers. The guard plate 7 acts to limit the movement of the cord between the fingers so that a positive engagement of the cord thereby is certain.

The forefinger of the operator is then drawn back to pull the latch 9 rearwardly upon the diverging arms or shanks 3 while the operator at the same time closes the handle to bring the fingers tightly together against the cord. The latch thus acts to maintain the jaws firmly closed and the operator is then enabled to give the necessary twisting and elevating movement to the instrument to remove the cord from the body of the chicken so that the same can be easily reached to be cut with a suitable instrument

From the foregoing description it will be

readily seen that the present instrument may be inexpensively made and is designed to enable the user to work quickly and accurately without a risk of injuring and possibly losing the fowl operated upon.

Having thus described my invention, what I claim is:—

1. An instrument of the character described, comprising a pair of pivotally connected jaws each terminating at its forward end in a laterally directed finger, said fingers being adapted to be brought into side by side contacting relation, a guard member carried by one of the jaws normally overlapping the adjacent jaw, and means for securing the jaws in closed position.
2. In an instrument of the character described, a pair of jaw members, means for pivotally connecting the jaws, fingers formed at the ends of the jaws remote from the pivot point and adapted to be brought into side by side relation, a guard plate carried by one of the jaws and normally overlapping the adjacent jaw and in close proximity to said fingers, and means normally preventing separation of said jaws beyond a predetermined distance adapted to be actuated for locking the jaws and fingers in contacting relation.
3. In an instrument of the character described, a pair of pivotally connected jaws, fingers carried by said jaws adapted to be brought into side by side contacting relation, a guard plate carried by one of the jaws and overlapping the adjacent jaw behind and in close proximity to said fingers, handle shanks carried by said jaws and extending through a portion of their length in divergent relation from a point adjacent the pivotal connection of the jaws, and a sliding latch member adapted when moved over the divergent ends of the shanks to lock the jaws and fingers in contacting relation.

In testimony whereof I hereunto affix my signature.

CLIFFORD F. CRIDLAND.
